(57) **CLAIM**

We claim the ornamental design for a tire tread for a model vehicle, as shown and described.

DESCRIPTION

FIG. 1 is a, top, right, front perspective view of a tire tread for a model vehicle;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top, right, front perspective view of a tire tread for a model vehicle mounted on a model vehicle platform. The broken line showing of a model vehicle platform is provided for the purposes of illustrating environmental structure; whereas, the broken line showing of features of the tire illustrate portions of the article that form no part of the claimed design.
